UNITED STATES PATENT OFFICE.

WILLIAM KOCH, OF NEW YORK, N. Y., ASSIGNOR OF ONE-HALF TO CHARLES HYAMS, OF SAME PLACE.

DESIGN FOR A QUILTING-PATTERN FOR SKIRTS.

SPECIFICATION forming part of Design No. 16,175, dated July 21, 1885.

Application filed June 30, 1884. Term of patent 7 years.

To all whom it may concern:

Be it known that I, WILLIAM KOCH, of the city, county, and State of New York, and a citizen of the United States, have invented and produced a new and original Design for Quilting Linings and Skirts, of which the following is a specification, reference being had to the accompanying drawing, forming part thereof.

10 The invention consists in the pattern hereinafter described.

The accompanying drawing is a plan view showing the quilted pattern stitched on the fabric.

15 A represents a series of hexagonal figures, two sides, *a*, in each figure being vertical and of less length than the other sides of the figure, each of these shown sides in the figures being opposite to the corresponding side in the 20 figures throughout the series, leaving a space,

b, between these shorter sides, and each of the longer sides of the hexagon, or the lines forming such sides, crosses at an angle, the sides of the adjacent hexagon forming thereby a series of diamond shaped patterns, B, and a series of small hexagonal patterns, C, as is shown in the drawing.

Having described my invention, what I claim as my design, and desire to secure by Letters Patent, is—

30 The pattern for quilting linings and skirts, consisting of series of hexagons A and series of rectangular spaces *b*, diamonds B, and hexagonal figures C, arranged and combined to produce the design shown in the accompanying drawing.

35 WILLIAM KOCH.

In presence of—

G. M. PLYMPTON,
D. A. CARPENTER.
